UNITED STATES PATENT OFFICE.

MAXWELL C. MAXWELL, OF STAMFORD, CONNECTICUT, ASSIGNOR TO THE YALE & TOWNE MANUFACTURING COMPANY, OF STAMFORD, CONNECTICUT.

COMBINED HOIST AND HOPPER.

1,395,858.

Specification of Letters Patent.

Patented Nov. 1, 1921.

Application filed February 17, 1921. Serial No. 445,614.

To all whom it may concern:

Be it known that I, MAXWELL C. MAXWELL, a citizen of the United States, and a resident of Stamford, in the county of Fairfield and State of Connecticut, have invented 5 certain new and useful Improvements in Combined Hoists and Hoppers; and I do hereby declare the following to be a full, clear, and exact description of the invention, 10 such as will enable others skilled in the art to which it appertains to make and use the same.

This invention relates to a combined hoist and hopper designed more particularly for 15 feeding steel chips or other material to electric furnaces.

With the constructions now in use the feed 20 hopper for the furnace is normally housed in a pit in the floor with its top edge flush with the surface of the floor and supported by a plurality of fingers or projections on the hopper resting in bearing plates on the floor. The steel chips or other material is dumped from trucks into the hopper, and 25 the latter is then transferred to the furnace by means of an overhead trolley hoist system, after which the door at the lower end of the hopper chute is opened and the contents of the hopper discharged into the 30 furnace.

Great trouble has been experienced in discharging the contents of the hopper into the furnace, due to the fact that the mass of material in the hopper becomes arched 35 and wedged therein, so that when the discharge door is opened, only the lower part of the contents passes out thus necessitating the use of mechanical devices to break the arch and free the material, and 40 while such devices have been effective to a certain extent, they fail to liberate the entire mass so as to insure the complete discharge of the contents of the hopper.

The object of my invention is to provide 45 means that will absolutely prevent any arching or wedging of the contents of the hopper thus insuring the free discharge of the entire contents of the latter into the furnace and it consists in the parts and combination of parts and in the details of construction as will be more fully explained 50 and pointed out in the claims.

In the accompanying drawings, Figure 1 55 is a view in side elevation showing a hopper in position to discharge its contents into

a furnace; Fig. 2 is a view in side elevation of the hopper; Fig. 3 is a view in plan and Fig. 4 a front elevation of the same; Fig. 5 is a view in side elevation of the cone; Fig. 6 is a plan view of the latter; Fig. 7 60 is a view partly in section and partly in elevation of the releasing device for the door, and Fig. 8 is a view similar to Fig. 1 of a modified form of trolley hoist for the hopper.

10 represents an inverted conical hopper provided at its bottom or smaller end with an inclined discharge chute 11 normally closed at its lower end by a door 12. This door is hinged at its upper end to the chute 70 so as to swing inwardly and upwardly when released, and it and the lower or free end of the chute are of a size to readily enter the feed opening 13 in the electric or other furnace 14. The chute 11 is preferably 75 made in two sections, so that the lower end or the part 15 thereof which enters the feed opening in the furnace and which is subjected to intense heat, may be removed and repaired or renewed and another substituted 80 as its condition may necessitate.

The section 15 of the chute preferably 85 forms in shape or contour to the shape of the feed opening 13 in the furnace and is of a size to readily enter the same, its penetration into said feed opening 13 being limited by the external flange 16 which engages the end wall of the furnace.

The door 12 is provided adjacent its free end with the hook shaped latch 17, the hook 90 18 of which passes through an opening 19 in the chute and engaging the wall of said opening locks the door in its closed position.

20 is the latch unlocking lever pivoted to the outer side of the chute 11 and provided at its lower end with a bent end 21 which is adapted when lever 20 is actuated, to engage the hook shaped end 18 of the latch and force the same inwardly thus releasing the door and permitting the contents of the hopper and chute to gravitate 95 into the furnace.

The hopper, like those in use, is normally housed in a pit in the floor with its top edge flush with the surface of the floor and supported by a plurality of fingers 22 secured to the hopper and resting on bearing plates located in the floor.

The hopper 10 is connected by hooks 23 and chains 24 with the drums or grooved 100 105 110

pulleys 25 on shaft 26 which is supported from the twin trolleys 27 adapted to travel on the lower flange of the track rail 28. Shaft 26 is rotated to elevate and lower 5 the hopper by the shaft 29 and gears 30, the shaft 29 being rotated by the actuating chain 34 passing around a grooved pulley on the end thereof in the usual and well known manner.

10 The principal feature of my invention consists of the hollow truncated cone 31 suspended from the hoist chain 32 carried by an auxiliary hoist 33 which is actuated to raise and lower the cone by the operating 15 chain 34. The part 31 is in the form of a truncated cone open at both ends and provided at its upper and smaller end, as shown in Figs. 5 and 6, with the oppositely disposed supporting bars 31^a which rest within 20 the pockets 35 in the upper edge of the hopper so that when the parts are assembled the cone will be supported by the hopper.

As shown in Fig. 1, the larger, lower end 25 of the cone is approximately the diameter of the hopper at the juncture of the latter with the chute, so that the metal chips or other material in the hopper, and at the outer side of the cone cannot pass into the chute 11 until the cone shall have been 30 raised, whereas the metal chips or other material within the truncated cone are free to flow out into the chute and into the furnace 14 when the door 12 of the chute is opened for the discharge of the contents. 35 There is no tendency of the chips or other material to arch or become wedged in the chute, or within the cone, hence upon opening the door 12 by the actuation of the lever 20 as described, the contents of the chute 40 and the cone will gravitate into the furnace. In filling the hopper, the chips or material not only fill the cone but also the space within the hopper at the outer side of the cone, hence if after the material within the 45 chute and cone have been discharged, or while it is being discharged, the cone be lifted by the auxiliary hoist 33 and its chain 32, the metal chips or other material within the hopper at the outer side of the cone 50 will fall into the chute and be discharged into the furnace.

By the use of a hollow cone within the hopper any arching of the contents of the hopper will be avoided, and the contents of 55 the hopper at the outer side of the cone will be broken up and loosened by the upward movement of the cone, thus causing the material at the outer side of the latter to gradually feed into the chute as the cone 60 is withdrawn from the hopper. It will also be seen that when the door 12 is opened, the contents of the chute and cone immediately discharge into the furnace and upon raising the cone by means of the auxiliary hoist, the mass of material within the hopper at

the outer side of the cone will be broken up and pass out into the furnace. After the contents of the hopper have been discharged the cone is lowered and the hopper raised or moved to disengage it from the furnace 70 and is then moved and lowered into its pit for recharging.

The construction shown in Fig. 8 is identical with that shown in Fig. 1 except that the auxiliary hoist for the cone is carried 75 by a band 36 mounted on a sleeve 37 which houses the operating shaft 26 of the twin hoists, the said sleeve 37 being suspended from the latter.

It is evident that many slight changes 80 might be resorted to in the relative arrangement of parts shown and described without departing from the spirit and scope of my invention, hence I would have it understood that I do not wish to confine myself to the exact construction and arrangement of parts shown and described but,

Having fully described my invention what I claim as new and desire to secure by Letters-Patent, is:—

1. The combination of a hopper and hoist mechanism for the same, a hollow truncated cone open at both ends and adapted to rest within the hopper and hoist means for lifting the cone independently of the hopper. 95

2. The combination of a hopper and hoist mechanism for the same, a hollow truncated cone supported by and within the hopper, and hoist means for lifting the cone independently of the hopper.

3. The combination of a hopper of greater diameter at the top than the bottom, hoist mechanism for the hopper, a hollow truncated cone the larger and lower end of which is approximately the size of the smaller end of the hopper and means for lifting the cone independently of the hopper. 105

4. The combination of a hopper of greater diameter at the top than the bottom, hoist mechanism for the upper, a hollow truncated cone the lower end of which approximates the size of the lower and smaller end of the hopper to form a choke for the same, the said cone being supported by and within the hopper and hoist mechanism for lifting the cone independently of the hopper. 110

5. The combination of an inverted conical shaped hopper, hoist means for the same, a hollow truncated cone supported by and within said hopper, a chute forming a continuation of the hopper, a door for closing the lower end of the chute and a latch operable from the outside of the chute for releasing the door. 115

6. The combination of an inverted conical hopper provided at its upper edge with projections for supporting the same in a position to be filled, hoist means for elevating and lowering the hopper, a chute forming a continuation of the latter, a door closing 120

the lower end of the chute, a latch for locking the door in its closed position and a lever operable from the outer side of the chute for disconnecting the latch and releasing the door.

7. The combination of an inverted conical hopper provided at its upper end with projections for supporting the same in a position to be filled, hoist means for elevating and lowering the hopper, a chute forming a continuation of the latter, a door closing the lower end of the chute, a latch for locking the door in its closed position, a lever operable from the outer side of the chute 10 and disconnecting the latch and releasing the door, a hollow truncated cone within and adapted to be supported by the hopper, 15

and hoist means for lifting and lowering the cone independently of the hopper.

8. The combination of an inverted conical hopper, hoist means for the same, a hollow truncated cone provided adjacent its upper end with projections adapted to engage the upper edge of the hopper and be supported by the latter and means for elevating and lowering the cone independently of the hopper.

In testimony whereof, I have signed this specification in the presence of two subscribing witnesses.

MAXWELL C. MAXWELL.
